[57] CLAIM

The ornamental design for a toner cartridge, as shown and described.

DESCRIPTION

FIG. 1 is a front elevational view of a toner cartridge showing our new design;

FIG. 2 is a rear elevational view;

FIG. 3 is a top plan view;

FIG. 4 is a bottom plan view;

FIG. 5 is a left side elevational view;

FIG. 6 is a right side elevational view;

FIG. 7 is a cross sectional view taken along line 1—1 in FIG. 3;

FIG. 8 is a right, front and top perspective view;

FIG. 9 is a front elevational view of a second embodiment of our new design of FIGS. 1-8;

FIG. 10 is a rear elevational view;

FIG. 11 is a top plan view;

FIG. 12 is a bottom plan view;

FIG. 13 is a left side elevational view;

FIG. 14 is a right side elevational view;

FIG. 15 is a cross sectional view taken along line 2—2 in FIG. 11; and

FIG. 16 is a right, front and top perspective view thereof.
